UNITED STATES PATENT OFFICE.

WINFIELD P. PORTER, OF NEW YORK, N. Y.

PNEUMATIC TUBE AND METHOD OF MAKING THE SAME.

Application filed January 30, 1922. Serial No. 532,704.

To all whom it may concern:

Be it known that I, WINFIELD P. PORTER, a citizen of the United States, a resident of the city of New York, in the county of the Bronx and State of New York, have invented a certain new and useful Improved Pneumatic Tube and Method of Making the Same, of which the following is a specification.

10 The invention relates to an inflatable inner tube for tires of the type wherein the tube is reinforced to minimize the danger of blowouts by a plurality of reinforcing strands or strips of fabric or the like, and 15 yet such strips or strands are so related to each other and to the body of the tube that the elasticity of the tube, both as regards longitudinal and lateral expansion or contraction, is not impaired. In other words, 20 the tube is left free, notwithstanding the reinforcement to adjust itself both in length or perimeter and in diameter or cross-sectional area.

One object of the invention is to provide 25 a tube of the above character of such structure as to facilitate its manufacture and the operations involved therein, particularly with regard to the proper disposition of the reinforcement in the walls of the tube.

30 The invention also includes a tube of the above type possessing reinforcement against rupture in all directions without impairment to its expansibility or adjustability above described.

35 Further objects and advantages of the invention will be in part obvious and in part specifically pointed out in the description hereinafter contained, which, taken in connection with the accompanying drawings, 40 discloses a preferred embodiment thereof; such embodiment, however, is to be considered merely as illustrative of its principle.

In the drawings—

45 Figure 1 is a view of a portion of a web of elastic material reinforced with strands such as are adapted for use in the invention, such view indicating the manner in which a web of the above character may be cut up to provide pieces for assemblage to form a tube in accordance with the invention;

50 Fig. 2 is an edge view of the web shown in Fig. 1;

Fig. 3 is a view showing pieces of the character obtained from the web illustrated

in Fig. 1, juxtaposed and united according to the method of making the tube;

Fig. 4 is an edge view of the structure shown in Fig. 3;

Fig. 5 is a top view of a tube made in accordance with the invention;

Fig. 6 is a side view of a composite tube of the above character constructed to provide reinforcement against rupture in all directions, certain portions of the tube being cut away;

Figs. 7, 8 and 9 are, respectively, cross-sectional, side and bottom views of the tube shown in Fig. 5.

In my prior United States Patent No. 1,394,787, dated October 25, 1921, and entitled "Pneumatic tire," I have shown an inner tube of the above type wherein the reinforcement is obtained by strips or strands of relatively strong material incorporated in the body of the tube, each of such strands having an intermediate portion at the belly of the tube and its end portions extending around the sides thereof at an inclination to the longitudinal axis of the tube, such end portions crossing at the tread, whereby the reinforcement takes the form of a series of parallel inclined Vs having their bases at the belly of the tube and their ends crossing at the tread. As a tube of the above type is inflated, the reinforcement becomes inclined less and less to a radial section through the tube, and such reinforcement permits proper expansion of its resilient walls, since as the Vs become less and less inclined, an increase in diameter of the tube results; furthermore, such Vs being also inclined to the longitudinal axis of the tube, permit the elastic material between the strands of the reinforcement to stretch and thus afford an increase in the perimeter of the tube conformable to its increase in radial section.

However, some difficulty is involved in incorporating the reinforcement into the elastic material of such a tube in case the operation involves forming the reinforcing strands into V or other angular shape, particularly if successive strands are to be properly spaced from and disposed parallel to each other. According to the present invention, I provide a tube of the above character but with such structure that the necessity of forming the reinforcing strands

into V or other angular shape is avoided and yet the tube resulting from the steps or methods of manufacture hereinafter specified is reinforced in such a manner as to provide the desired expansibility. In the preferred form of the invention, the tube is furthermore, so constructed that readily available reinforcing materials, such as cord fabric, may be employed.

10 Referring to the drawings, I have illustrated in Fig. 1 a web 1 of elastic material, such as rubber or rubber composition, having incorporated therein a plurality of parallel, slightly spaced, reinforcing strands 2. 15 The web shown in Fig. 1 may be obtained by laying down wholly unconnected strands 2 and coating the same on opposite sides with rubber or the like, but I prefer to employ a cord fabric for this purpose, such 20 fabric consisting of the longitudinal or warp reinforcing strands 2 tied together by means of fine weft threads 3 which serve to insure that the strands 2 will be maintained in proper relation to each other during the 25 operation of forming the web and which are yet so fragile as to have no effect upon the expansibility of the tube after completion. In other words, the fine threads 3 are so weak that they become severed as soon as 30 any substantial strain is placed upon them. Such threads, therefore, are not illustrated in Figs. 5 to 9 of the drawings.

The web of material such as is above described may then be cut on the bias to provide 35 a plurality of pieces 4, each piece having the reinforcing strands 2 running at an angle to the side edges thereof. As indicated in Fig. 3, pieces 4 of the character above described may then be laid down 40 side by side with one piece reversed so that the reinforcing strands 2 in the respective pieces are oppositely inclined to the adjacent side edges of the pieces; such side edges are then suitably secured together, 45 being slightly overlapped, if desired, and cemented by strips of rubber 5 (Fig. 4) placed along both sides of the juncture.

Thus the reinforced elastic sheet made up 50 of pieces 4 above described will contain reinforcing strands which are of angular or V-shape and yet the expensive and difficult operations of forming individual strands into such shape is avoided.

The reinforced sheet may then be suitably 55 formed into tubular shape,—for example, by wrapping the same around a pole with the apices of the angles between the reinforcing strands 2 at the belly of the tube to be formed and the side edges of the sheet 60 overlapping at the tread thereof, whereby the reinforcing strands in the above-mentioned sides of the sheet will form a crossed reinforcement in the tread of the tube.

The tube may then be vulcanized and 65 cured in any suitable manner,—for example,

as described in my prior Patent No. 1,394,- 787 above-mentioned, a compression tread 6 (Fig. 7) being built up upon the overlapping sides of the sheet, if desired, so as to protect the tube against puncture.

70 For clearness, the outlines of the overlapping sides of the reinforced sheet are preserved in Fig. 5 to show more plainly the relation of the parts of the sheet in the completed product, but it will be understood that after the tube has been vulcanized and cured as above described, such outlines will be indistinguishable. The lower end of the sheet, as the same appears in Fig. 5, is also cut parallel to the length of the reinforcing 80 strands 2 to indicate the inclination of such strands to a radial section of the tube.

Thus it will be seen that the sides of the completed tube are reinforced by a plurality of strands which run inclined to both the longitudinal and transverse dimensions of the tube and thereby permit proper changes of shape therein. In some instances, particularly where a tube is to be employed upon vehicles carrying very heavy loads, it 90 may be desirable to reinforce the tube, particularly at its sides, more strongly against rupture due to blowouts, and yet it will be obvious that the expansibility of the tube should not thereby be impaired. In Fig. 6 I 95 have illustrated a composite tube possessing the above qualities and consisting of an inner tube 7 having its reinforcing strands 2^a extending in one direction and an outer tube 8 freely movable with reference to the 100 inner tube 7 and having its reinforcing strands 2^b oppositely inclined so as to cross over the strands 2^a previously described. Thus, as the composite tube is inflated, both tubes 7 and 8 may expand freely and yet the crossed reinforcing strands 2^a and 2^b will 105 provide reinforcement against blowouts in all directions. If desired, the tubes 7 and 8 may be united adjacent the usual valve 9 to maintain the latter in proper position.

110 From the foregoing description it will be noted that an inner tube having reinforcing strands disposed in accordance with the invention will contain one group of such strands extending partially around the tube in a diagonal direction,—for example, the strands shown at the right of Fig. 5, and another group of similar strands extending around another portion of the tube from 115 points adjacent one of the ends of the first-mentioned group. This last-mentioned group of strands, for example, will be the strands at the left of Fig. 5. In the illustrated embodiment of the invention, the 120 above-mentioned adjacent ends of the strands are located at the belly of the tube, while the remaining ends of such groups of strands overlap at the tread to form a 125 crossed reinforcement therein.

130 While a specific embodiment of the invention

tion has been described, it is obvious that many changes may be made therein without departing from the spirit of the invention as defined in the following claims.

5. What I claim and desire to secure by Letters Patent is:
1. The method of making an inner tube which comprises uniting side edges of pieces of elastic material containing parallel reinforcing strands running at opposite angles to such side edges to make up a sheet and forming such sheet into a tube.
  2. The method of making an inner tube which comprises uniting side edges of pieces of elastic material containing parallel reinforcing strands running at opposite angles to such sides to make up a sheet having a V-shaped reinforcement and forming such sheet into a tube.
  20. 3. The method of making an inner tube which comprises uniting side edges of pieces of elastic material containing parallel reinforcing strands running at opposite angles to such sides to make up a sheet having a V-shaped reinforcement, folding such sheet into tubular shape with the apices of the aforesaid angles at the belly of the tube and the remaining side edges of the sheet at the tread of the tube.
  30. 4. The method of making an inner tube which comprises uniting side edges of pieces of elastic material containing parallel reinforcing strands running at opposite angles to such sides to make up a sheet having a V-shaped reinforcement, folding such sheet into tubular shape with the apices of the aforesaid angles at the belly of the tube and the remaining side edges of the sheet overlapping substantially at the tread of the tube, whereby the reinforcing strands in the above-mentioned sides of the sheets form a crossed reinforcement in the tread.
  45. 5. The method of making an inner tube which comprises severing on the bias a web of elastic material containing parallel reinforcing strands to form pieces with the strands running at an angle to side edges thereof, uniting side edges of such pieces with the strands oppositely inclined to such edges to make up a sheet and forming such sheet into a tube.
  55. 6. An inner tube having elastic walls, a group of parallel reinforcing strands therein extending only partially around the tube and diagonally inclined to the length thereof, and another group of parallel reinforcing strands extending only partially around another portion of the tube from points adjacent one of the ends of said first-mentioned group, said last-mentioned group of strands being also diagonally inclined to the length of the tube, and the adjacent ends of said groups being angularly related.
  60. 7. An inner tube having elastic walls, a group of parallel reinforcing strands therein extending from the belly of the tube around one side to the tread thereof, such strands being diagonally inclined to the length of the tube, and another group of parallel reinforcing strands extending from the belly of the tube around the other side thereof to the tread, said last-mentioned group of strands being similarly diagonally inclined to the length of the tube, whereby the adjacent ends of said groups form a V-shaped reinforcement with their apices at the belly of the tube.

8. An inner tube having elastic walls, a group of parallel reinforcing strands therein extending from the belly of the tube around one side to the tread thereof, such strands being diagonally inclined to the length of the tube, and another group of parallel reinforcing strands extending from the belly of the tube around the other side thereof to the tread, said last-mentioned group of strands being similarly diagonally inclined to the length of the tube, whereby the adjacent ends of said groups form a V-shaped reinforcement with their apices at the belly of the tube.
90. 9. A composite inner tube comprising an inner tubular member having elastic walls, parallel reinforcing strands in said walls extending around the sides of such member and similarly diagonally inclined to the length thereof on opposite sides of the tube, and an outer tubular member having similar reinforcing strands thereon but inclined in the opposite direction from the strands of the first-mentioned tubular member, said members being free to shift relative to each other and being substantially unconfined except for the reinforcing strands aforesaid.
100. 10. A composite inner tube comprising an inner tubular member having elastic walls, parallel reinforcing strands in said walls extending around the sides of such member and providing a V-shaped reinforcement similarly inclined to the length of the tube on opposite sides thereof and with the apices of the V at the belly thereof, and an outer tubular member having similar reinforcing strands therein but inclined in the opposite direction from the strands of the first-mentioned tubular member, said members being free to shift relative to each other and being substantially unconfined except for the reinforcing strands aforesaid.

In testimony that I claim the foregoing, I have hereunto set my hand this 19th day of January, 1922.

WINFIELD P. PORTER.
